Patented Mar. 26, 1918.

FIG. 4

Richard T. Hosking, INVENTOR

BY

Geo. B. Willcox, ATTORNEY

UNITED STATES PATENT OFFICE.

RICHARD T. HOSKING, OF SAGINAW, MICHIGAN, ASSIGNOR TO AMERICAN BANKING MACHINE CORPORATION, OF SAGINAW, MICHIGAN, A CORPORATION OF DELAWARE.

COIN-STACKING DEVICE FOR VENDING-MACHINES.

1,260,382.

Specification of Letters Patent. Patented Mar. 26, 1918.

Original application filed July 17, 1913, Serial No. 779,420. Divided and this application filed June 18, 1917. Serial No. 175,483.

To all whom it may concern:

Be it known that I, RICHARD T. HOSKING, a citizen of the United States, residing at Saginaw, in the county of Saginaw and 5 State of Michigan, have invented certain new and useful Improvements in Coin-Stacking Devices for Vending-Machines; and I do hereby declare the following to be a full, clear and exact description of the 10 invention, such as will enable others skilled in the art to which it appertains to make and use the same.

This invention relates to coin stacking devices for vending machines and pertains 15 more particular to stacking devices adapted for use in conjunction with a vending machine in which is employed an upright coin-receiving receptacle or tube, and a movable slide adapted to carry a coin forward and 20 introduce it into the lower end of the tube through a slot provided in the tube for that purpose. A vending machine of this type is adapted to stack the coins in sequence, that is, in the order in which the coins are 25 deposited on the slide.

A vending machine of this type is illustrated and described in my co-pending application, Serial No. 779,420, of which the present is a divisional application.

30 My present improvement pertains more specifically to an improved construction of the feeding-in slide and devices employed in conjunction therewith, whereby a coin deposited in the slide is fed forward into the 35 tube through the slot and is automatically tilted at its forward or advancing edge and is raised as it passes into the tube, lifting the coins which are already in the tube, and is finally deposited in a substantially horizontal 40 position in the tube and supported at such a height above the slide that the slide can be retracted and returned to its original position without disturbing the coin which has just been deposited in the tube.

45 With the above and certain other objects in view which will appear later in the specification, my invention comprises the devices described and claimed and the equivalents thereof.

50 In the drawings, Figure 1 is a top plan view of a coin-stacking device embodying my invention.

Fig. 2 is a longitudinal section, taken on

the line 2—2 of Fig. 1, showing the slide in 55 its retracted or initial position.

Fig. 3 is a similar view showing the slide pushed in to insert a coin in the stacking tube.

Fig. 4 is a perspective view, broken away 60 in part, showing a modified construction of the slide.

As is clearly shown in the drawings, 1 indicates the coin receptacle or tube, 2 the feeding-in slide, 3 the base-plate on which 65 the slide 2 operates, and 4 the frame.

The slide 2 is preferably formed of a metal plate.

5 designates a coin of the desired denomination, the coin being supported preferably 70 on the base plate 3. The slide is normally held in its retracted position, as shown in Fig. 2 by means of a spring 6, one end of which is secured to the frame 4 and the other end secured to the bracket 2^a attached to 75 the movable slide 2.

The tube 1 is provided at its lower end with a coin slot 7 and just within the tube and at the rear of the slot is an upwardly inclined guide 8, preferably formed by striking up 80 the metal of the base plate 3, as shown in Figs. 1 and 2.

To the rear of the inclined guide 8 is located a coin-supporting member or table 9, which is preferably formed integral with 85 the tube 1, being in effect a partial bottom for the tube.

On the feeding-in slide 2 and at the edge of the recess 5 is a feeding-in projection 10, preferably formed by striking up the metal 90 of the feeding-in slide 2, as shown in Figs. 1 and 2, although the projection 10' may, if desired, be formed as shown in Fig. 4, comprising one or more points projecting upwardly from the surface of the feeding in 95 slide 2 and located at the edge of the recess 5. In front of the advancing edge of the coin and in front of the recess 5 and carried by the feeding-in slide 2 is located a pair of hooks or projections 11, the purpose of 100 which will be explained presently.

The operation of the device is as follows:

A coin having been deposited in the recess 5 of the slide 2, the slide is pushed forward, the projections 11 or 11' moving past the 105 sides of the inclined guide 8 and under the bottom 9 of the tube 1. The advancing edge

- of the coin slides up along the inclined guide 8, tilting the coin and forcing it up underneath the coins already in the tube and between those coins and the coin-support 9, lifting the coins already in the tube. As the coin passes over the top of the guide 8 and assumes a more nearly horizontal position, the opposite edge of the coin is engaged by the upper part of the feeding-in projection 10, as shown in Fig. 3. Continued forward movement of the slide causes the projection 10 to push the coin clear into the tube. The coin is now out of contact with the slide 2 and rests upon the support 9 at a sufficient height above the slide 2 to be out of contact therewith, so that the slide, when released and retracted by spring 6 will move back to its initial position without touching or disturbing the deposited coin.
- If it happens that the coin 2 is pushed in only part way and the slide 2 is released before it reaches the end of its travel, the hooks 11 will draw the coin back with the slide so that a coin not properly deposited in the tube 1 will be returned.

By the means above described I have provided a simple, yet effective coin stacking device by which the coin is fed into the tube

and automatically deposited therein in a raised position above the feeding-in slide, so that the slide may be returned to its initial position, without further contact with the coin.

Having thus described my invention, what I claim and desire to secure by Letters Patent is:

In a coin-stacking device, a base, a coin-tube formed with a slot and located above said base, a feeding-in slide longitudinally movable on said base, said slide formed with a coin receiving recess, an upwardly and rearwardly inclined guide mounted on said base and located within said tube at the rear of said slot, a coin support in said tube located at the rear of said inclined guide and above the path of travel of said slide, and a projection on said slide extending above the upper surface thereof at the edge of said coin-receiving recess for the purposes set forth.

In testimony whereof, I affix my signature in presence of two witnesses.

RICHARD T. HOSKING.

Witnesses:

NELLIE M. ANGUS,
ROY WALLIS.
